UNITED STATES PATENT OFFICE

2,548,069

COTTON PICKER SPINDLE SLAT FASTENING
MEANS

John D. Rust, Memphis, Tenn.

Application April 2, 1946, Serial No. 658,967

18 Claims. (Cl. 56—42)

1

My invention relates to cotton picking machines in general and more particularly to the kind disclosed in United States Patents No. Re. 19,411, issued January 1, 1935; No. 1,894,198, issued January 10, 1933; No. 2,023,491, issued December 10, 1935; No. 2,058,513, issued October 27, 1936; No. 2,058,514, issued October 27, 1936; No. 2,085,046, issued June 29, 1937; and No. 2,162,750, issued June 20, 1939.

The present invention has for its object to provide an improved hinge for the spindle slats which hinge will serve several purposes, namely, first to pivot the slats, second, to determine the angle of the spindles when in the picking position, third, to determine the stripping angle of the spindles, fourth, to act as a guide for the upper and lower spindle moistening rings, fifth, at least one hinge to carry a lug for actuating the moistening device, sixth, to enable the quick detaching and attaching of slats for replacement or repair and seventh, to provide for locking of the hinges in place without the use of screws or bolts.

Other objects will in part be obvious and in part be pointed out hereinafter.

To the attainment of the aforesaid objects and ends, the invention further resides in the novel details of construction, combinations and arrangements of parts all of which will be first fully described hereinafter and then be specifically pointed out in the appended claims, reference being had to the accompanying drawings in which:

Fig. 1 is a detail top plan view illustrating how my improved hinges operate to determine the stripping angle of the spindles and how the hinges act in cooperation with the spindle moistening device.

Fig. 2 is a detail top plan view showing how the hinges cooperate with one another to determine the position of the spindles at the mid-picking position.

Fig. 3 is an enlarged detail vertical section on the line 3—3 of Fig. 4.

Fig. 4 is a top plan view of the hinge and slat shown in Fig. 3.

Fig. 5 is a detail perspective view of a portion of the hinge of the first embodiment of my invention.

Fig. 6 is a perspective view of one of the keys.

Fig. 7 is a top plan view of a modified construction of hinge, a hinge-locking key being shown in dotted lines.

Fig. 8 is a side elevation of the hinge shown in Fig. 7.

Fig. 9 is a side elevation of the key used with the hinge of Fig. 8.

2

Fig. 10 is a top plan view of the key.

Fig. 11 is a view similar to Fig. 3 showing the second embodiment of my invention.

Fig. 12 is a plan view, parts being broken away, of a cotton picking machine embodying my invention.

Fig. 13 is a side elevation showing a further modification of my invention.

Fig. 14 is a central vertical longitudinal section of the embodiment shown in Fig. 13.

Fig. 15 is a detail vertical cross section on the line 15—15 of Fig. 14.

Fig. 16 is a detail section on the line 16—16 of Fig. 14.

15 Referring now to the accompanying drawings in which like numerals and letters of reference indicate like parts in all the figures, 1 indicates a Rust cotton picking machine, 2 and 3 the conveyor shafts and 4 the sprockets about which the chains 5 pass which chains carry pins 6 to which the hinges of the slats are pivoted. All the above numbered parts are well known and per se are not of the present invention.

The present application, which involves two 25 embodiments of my invention, is a continuation in part of an application filed by me on March 29, 1944, Serial No. 528,586, now Pat. No. 2,440,450.

The first form of my invention is illustrated on Sheet 1 of the drawings by reference to which it will be seen that 7 indicates the picking spindles each of which has an operating roller 8. The spindles are mounted in slats the construction of which per se is not claimed herein but constitute the subject matter of my patent aforesaid. Briefly

30 then each slat includes a retaining clip 9 over the wood bearing strip 10, felts 11, 12 and fiber strips 13. The rear wood bearing block is indicated by 14 and the metal housing therefor is indicated by 17. A fiber strip 13 and felt 37 are also provided for the rear spindle bearing. The retaining clip 9 includes the transverse plate 15 which has an upstanding lug 32.

35 16 indicates the top flanges of an end rib which are spaced from the plate 15 to form a hinge-leg-receiving channel.

A fixed rail 18 or track-backing bar 18 mounted on vertical supports 42 braces the track 19, 20, 21 on which the spindle rollers 8 run to turn the spindles. As the part 18 to 21 inclusive and 42 40 constitute per se no part of the present invention further description thereof is unnecessary, but see my patent aforesaid.

The hinges for the top and bottom of a slat being of the same construction only one end of a 45 slat has been shown with its hinge. Each hinge

comprises a rectangular plate 22 having a hole 23 to receive a hinge pin or rivet 6, an offset portion 24 bent down as at 25 and forwardly to provide a leg 26 which lies in a plane parallel to that containing the plate 22 but to one side of the same a distance such that when the several hinges are positioned as shown in Fig. 2 the distance between adjacent spindles 7 will equal the distance between adjacent pins 6. The offset portion 24 is so shaped (see Fig. 2) that the portion 24 of one hinge will lie against the curved part of plate 22 of the next adjacent plate and the plates 22 are of such width that when the spindles are passing through the stripping mechanism (not shown) and the moistening device (35, Fig. 1) the side edges of one plate 22 will lie parallelly against the adjacent side edges of adjacent plates thus determining the picking and doffing etc. positions, respectively, of the spindles.

Each leg 26 has a slot 27 and a shallow stop rib 28. The slot 27 receives the tongue 30 of the key 29 that fits between the leg 26 and the plate 15 and by reason of the stop 28 engaging the flanges 16, prevents the hinge from being accidentally withdrawn after the parts have been assembled as shown in Fig. 3. The key 29 has a flange 31 that rises above the stop 28 so that by forcing the tongue 30 down below the level of the bottom face of the leg 26, the key may be driven or pulled out by force applied to flange 31.

In Fig. 1 a set of moistener rings 35 is positioned adjacent the spindle slats in such a manner that the rows of spindles project between the rings and serve to support the intermediate rings of the series at one point, the hinge plates 22 cooperating by holding the top and bottom rings in their proper path at the same point of a triangular support, the entire set of rings being held at the other two points of support by the discs 34 on the shafts 33. The cooperating support of the hinge plates and the rows of spindles may be more clearly seen in Fig. 16 of my Patent No. 2,440,450, aforesaid.

The second embodiment of my invention includes matter not specifically shown and described in my original application aforesaid. This second form of my invention does not differ in principle from the original form and those parts which correspond in purpose and function to like parts in the first illustrated form bear the same reference number plus the index letter *a* and need not be re-described here.

The leg 26^a of the hinge (Figs. 7, 8 and 11) differs from the leg 26 (Figs. 3, 4 and 5) in that in place of the slot 27 a boss 36 is stamped in the leg, forming in the process, a recess 27^a. The top flange 16^a of the rib instead of being formed by bending over the sides of the metal and leaving a space as shown in Figs. 3 and 4, is solid across save for a hole 38 to receive the boss 36 as clearly shown in Fig. 11.

The key 29^a differs from the key 29 in that it is formed of thinner metal and has two transverse depressions 39 and 40 bent into it and the tongue 30^a is bent to form a lug 41 to fit within the recess 27^a when the parts are assembled. The portions 39 and 40 bear upon the ends of the slats when the key 29^a is driven into place. The metal of which key 29^a is made is sufficiently springy and the lug 41 is so shaped that by striking the flange 31^a in a direction from right to left in Fig. 11, the key may be driven out without having to hold down the tongue 30^a with a suitable tool.

One or more of the hinge plates 22 carries a

bracket 44 with a lug 45 to operate the moistening mechanism. As the moistening mechanism operating mechanism forms no part of the present invention it has not been illustrated in the accompanying drawings but see my patent aforesaid.

In the modification shown in Figs. 13 to 16, the retainer clip tongue plate shown at 15 in Fig. 3 is omitted and the clip is formed with a top 44 that lies over the side flanges 16^b, the rear edge 44^b of the top 44 being flared to facilitate passage of the boss 36^b as the leg 26^b is inserted. The top 44 is also provided with a slot 9^b to receive the boss 36^b and with a hole 9^b to line up with a hole 26^b in the leg 26^b, the holes 9^b and 26^b lying above the tongue 30^b in the locking key 29^b.

The end of the leg 26^b is further tapered as at 26^x to aid in the introduction of the leg into the space below the top 44 and also facilitate the introduction of the key 29^b. The end of the tongue 30^b in this embodiment is squared off so as to prevent any possibility of the end working out of the recess 27^b accidentally.

In Figs. 13 to 16 those parts which correspond to like parts in the preceding figures bear the same reference number plus the index letter *b* so repetition of their description is not necessary here.

From the foregoing description taken in connection with the accompanying drawings it is thought the construction, operation and advantage of my invention will be clear to those skilled in the art.

I claim:

1. In a cotton picking machine, means for releasably connecting a spindle-carrying slat having an end passage to endless conveyor elements, said means including a hinge element and a locking key cooperating in said passage for detachably connecting the conveyor elements and slats, each of said hinge elements comprising a plate with a pivot-aperture and parallel sides, a leg offset from said plate and lying in a plane parallel to but spaced from said plate, said leg having a lug and a recess intermediate its ends, said passage having a wall with a slot to receive said lug; said locking key being insertable in said passage between said leg and the inner wall of said passage and having a springy tongue with a lug to engage in the recess of said leg to retain the leg in said passage.

2. In a cotton picking machine, means for releasably connecting spindle-carrying slats each having an end passage to conveyor chains, said means including a hinge element having a portion provided with a stop lug and with a slot, said portion being capable of being passed through said passage, said hinge including a second portion bent back over the first portion and having provision for attachment to a conveyor chain; and a locking key insertable in said passage and having a tongue with a portion to snap into said slot for purposes described.

3. In a cotton picking machine, means for detachably connecting spindle-carrying slats to conveyor chains, said slats each having an end passage, a hinge element having a portion provided with a stop lug and with a slot, said portion being capable of being passed through said passage, said hinge element including a second portion bent back over the first portion and having provision through the medium of which it may be attached to the conveyor chain; and a locking key insertable in said passage and having a tongue to snap into said slot for purposes de-

scribed, and a bracket with a lug carried by one of the hinge elements for purposes described.

4. In a cotton picking machine, means for connecting spindle-carrying slats each having end passages to upper and lower endless carrying members, said means including hinge elements pivotally secured to the carrying members and having a snap-on connection to the slats, said hinge elements each including a plate having a bent-back portion constituting a leg spaced from the plate, said leg being adapted to be passed into said passage, and a locking key insertable in said passage and having means to engage the slat and the leg and to hold the leg against being moved in one longitudinal direction, the bend between the plate and the leg serving to prevent leg-movement in the opposite direction.

5. In a cotton picking machine, means for connecting spindle-carrying slats, having end passages, to endless carrier elements, said means including a hinge element having a plate portion having a hole for a pivot pin and having a leg to lie in said passage and having a stop to engage a part of the slat to prevent leg movement in one direction, and having a tongue receiving slot; a locking key insertable in said passage in a direction the reverse of that of said leg, said tongue adapted to spring into said slot to hold the leg against being withdrawn.

6. In a cotton picking machine, means for connecting spindle-carrying slats, having transverse end passages, to an endless carrier, said means including hinge elements, each of said hinge elements comprising a plate with a pivot-aperture and parallel sides, a leg offset from said plate and lying in a plane parallel to but spaced from said plate, said leg having a lug and a recess intermediate its ends, said passage having a wall with a slot to receive said lug, and a locking key insertable in said passage between said leg and the inner wall of said passage and having a springy tongue with a lug to engage in the recess of said leg to retain the leg in said passage.

7. In a cotton picking machine, means for connecting spindle-carrying slats to an endless conveyor, said means including snap-on hinge elements, means for rigidly holding said elements on the top and bottom ends respectively of said slats and having provisions for pivotal connections to the endless conveyor, said hinge elements each having a rectangular plate with a pivot hole and a rounded corner whose center of curvature is that of said hole, said elements having a leg, means cooperative with said legs and with the slats for releasably locking said leg to said slat.

8. In a cotton picking machine, means for connecting spindle-carrying slats to an endless conveyor, said means including snap-on hinge elements, means for rigidly holding said elements on the top and bottom ends respectively of said slats and having provisions for pivotal connections to the endless conveyor, said hinge elements each having a rectangular plate with a pivot hole and a rounded corner whose center of curvature is that of said hole, said elements having a leg, means cooperative with said legs and with the slats for releasably locking said leg to said slat, means for mounting said hinged slats on the endless conveyor at points equal to the distance between the centers of said pivot holes of adjacent hinges, all being arranged so that the several slats will be held, by contact between adjacent hinge plates, in the desired picking and doffing positions.

9. In a cotton picking machine, spindle-carry-

ing slats, each slat having an end passage, a hinge element having a portion provided with a stop lug and with a slot, said portion being capable of being passed through said passage, said hinge including a second portion bent back over the first portion and having provision for attachment to conveyor elements; and a locking key insertable in said passage and having a tongue to snap into said slot for purposes described.

10. In a cotton picking machine, spindle-carrying slats, each slat having an end passage, a hinge element having a portion provided with a stop lug and with a slot, said portion being capable of being passed through said passage, said hinge including a second portion bent back over the first portion and having provision for attachment to endless conveyors; and a locking key insertable in said passage and having a tongue to snap into said slot for purposes described, and a bracket with a lug carried by one of the hinge elements for purposes described.

11. In a cotton picking machine, means releasably connecting spindle-carrying slats to endless carriers, said slats having an end passage, said means including a hinge element and a locking key cooperating in said passage for detachably connecting the hinge element and a slat, said hinge element comprising a plate with a pivot-aperture and parallel sides, a leg offset from said plate and lying in a plane parallel to but spaced from said plate, said leg having a lug and a recess intermediate its ends, said passage having a wall with a slot to receive said lug; and a locking key insertable in said passage between said leg and the inner wall of said passage and having a springy tongue with a lug to engage in the recess of said leg to retain the leg in said passage, said wall and said leg having aligning holes for access to said tongue by a suitable tongue-releasing tool.

12. In a cotton picking machine, means for releasably connecting spindle-carrying slats to endless carrier elements, said slats each having an end passage, said means including a hinge element having a plate portion with a hole for a pivot pin and having a leg to lie in said passage and having a stop to engage a part of the slat to prevent leg movement in one direction, and having a tongue receiving slot; a locking key insertable in said passage in a direction the reverse of that of said leg, said tongue adapted to spring into said slot to hold the leg against being withdrawn, and means by which access to said tongue may be had by a suitable tongue-releasing tool.

13. Means for connecting spindle-carrying slats to conveyor chains, said means including hinge elements adapted for connection to the chains and slats, said elements each including a flat plate having a portion bent back upon itself and constituting a leg spaced from the plate for engaging the slat, the slat having a passage to receive said leg, and a releasable locking key cooperatively engaging with said leg and the slat for holding the leg to the slat.

14. Means for connecting spindle-carrying slats to conveyor chains, said means including hinge elements adapted for connection to the chains and slats, said elements each including a flat plate having a bent-back portion constituting a leg spaced from the plate for engaging the slat, the slat having a passage to receive said leg, and a releasable locking key cooperating with said leg and the slat for holding the leg to the slat, said locking key including a springy tongue and said leg having a recess to be cooperatively en-

gaged by said tongue when said key is in a locking position.

15. Means for connecting a spindle-carrying slat to conveyor chains, the slat having a passage at each end, said means including hinge elements, each hinge element including a flat plate adapted for connection to a chain and having a portion bent back upon itself and constituting a leg spaced from the plate and adapted to enter a slat passage, and means for locking said legs in said passages.

16. Means for connecting a spindle-carrying slat to conveyor chains, the slat having a passage at each end, said means including hinge elements, each hinge element including a flat plate adapted for connection to a chain and having a bent-back portion constituting a leg spaced from the plate and adapted to enter a slat passage, and means for locking said legs in said passages, said locking means including a locking key insertable in said slat passages between said legs and the slat and having means to effect a locking action between said legs and said slat.

17. Means for releasably securing a spindle-carrying slat of a cotton picking machine to a conveyor chain of the same, the slat having a passage at one end, said means including a hinge element comprising a rectangular plate having a pivot hole and a rounded corner whose center of curvature is that of said hole, said hinge ele-

ment having a leg, to enter said passage, and having means to effect a locking engagement with the leg and the slat.

18. Means for releasably securing spindle-carrying slats to chain members, the slats having a transverse passage at their ends, said means including hinge elements, each comprising a rectangular plate with a pivot hole and a rounded corner whose center of curvature is that of the hole, said element having a leg, means cooperating with said leg and with the slat for releasably locking said leg to said slat, the distance between the centers of the pivot holes of adjacent hinge elements being equal to the center-to-center length of a chain link, by virtue of which the several slats will be held, by contact between adjacent hinge plates, in the desired picking and doffing positions.
